UNITED STATES PATENT OFFICE.

MICHAEL LIPTAK, OF MINNEAPOLIS, MINNESOTA.

FURNACE-ARCH FOR BOILERS.

1,326,752.

Specification of Letters Patent. Patented Dec. 30, 1919.

Application filed February 9, 1918. Serial No. 216,152.

To all whom it may concern:

Be it known that I, MICHAEL LIPTAK, residing at Minneapolis, in the county of Hennepin and State of Minnesota, have invented 5 certain new and useful Improvements in Furnace-Arches for Boilers; and I do hereby declare the following to be a full, clear, and exact description of the invention, such as will enable others skilled in the art to 10 which it appertains to make and use the same.

My invention has for its object to provide an improved furnace arch for boilers or steam generating plants; and to such ends, 15 generally stated, the invention consists of the novel construction and combinations of parts hereinafter described and defined in the claims.

The general nature and purpose of the 20 furnace arches used in the combustion chambers of steam boilers is well known.

My invention provides particularly, an improved arrangement of interlocking arch forming blocks and supporting beams which 25 make the erection of the fire arch, in the first instance, an easy matter and which also make it an easy matter to maintain the same by replacement, from time to time, of those blocks of the arch that have been burned 30 away or damaged by the intense heat from the furnace. This improved fire arch involves as a radically new feature, a double layer arrangement of interlocking blocks so disposed in respect to each other and to the 35 supporting beams that the blocks that are directly hung on the beams are not exposed to the flames, or otherwise stated, blocks exposed to the direct action of the flames are not directly hung on the metal beams but 40 are indirectly hung from hanger blocks which, in turn, are hung from the supporting beams and thereby protected from the flames. The blocks that are directly hung from the supporting beams are designated 45 as "hanger blocks", while the blocks that are hung from the hanger blocks so that they are at the under surface of the arch and exposed to the direct action of the most intense flames, are designated as "underfacing 50 blocks". There are ample air spaces between the hanger blocks and underfacing blocks and between the hanger blocks and the metal beams so that the beams will always be kept cool.

55 The preferred form of the arch is illustrated in the accompanying drawings where-

in like characters indicate like parts throughout the several views.

Referring to the drawings,

Figure 1 is a vertical section taken through the fire box and arch on the line 2—2 of Fig. 2, some parts being shown in full;

Fig. 2 is a transverse section, the right hand half thereof, being a section on the line 2—2 of Fig. 1, and the left hand half thereof, being a section on the line 2'—2' of Fig. 1, and some parts being removed;

Fig. 3 is a perspective view of the arch, some parts being removed and some parts being sectioned; and

Fig. 4 is a transverse vertical section illustrating a slightly modified construction of the blocks.

The customary masonry of the furnace is indicated by the numeral 4, and the grate by 75 the numeral 5. The numeral 6 indicates the flues and the numeral 7 the head of an ordinary water tube boiler.

The furnace arch occupies the usual position and closes the space between the side 80 and front walls of the masonry, and the front ends of the lower flues 6, in accordance with my invention, are constructed as follows:

The main supporting beams of the arch 85 are, as shown, two in number and they are transversely extended, their ends being embedded in the side walls of the masonry. Preferably, the front main supporting beam is in the form of a steel or iron channel 8 90 while the innermost or front main beam is in the form of a steel or iron I-beam 9. A multiplicity of laterally spaced supplemental beams are hung from the lower flanges of the main beams 8 and 9; and these supplemental beams 10 are preferably steel or iron I-beams having relatively narrow flanges at their upper edges and relatively wide flanges at their lower edges. To thus hang or suspend the supplemental beams 10 from 95 the main beams 8 and 9, I provide said supplemental beams on their upper edge flanges with longitudinally slidably coupling brackets 11, 12 and 13, which are alike, except that the brackets 11 are longer than the brackets 100 12 and 13. All of the said brackets are provided at their ends with projecting hanger lugs that engage over the lower flanges of the adjacent main beams, as shown in Figs. 1 and 3. The hanger brackets 12 and 115 13 are alike but are faced in opposite directions. To interlock the said hanger brackets

with the upper flanges of the supplemental beams 10 they are formed with longitudinal T-shaped grooves in their lower faces, and to secure them in working position, as 5 shown, they are preferably provided with suitable set screws 14.

For an important purpose which will hereinafter appear, the supplemental beams 10 are provided at their inner ends with 10^a detachable beam tips 10^a, the flanges of which correspond to the flanges of the said beams 10, but the upper inner portions of which are preferably cut away on rectangular lines, as best shown in Fig. 3. The narrow 15 upper flanges of the said beam tips 10^a are telescoped into the projecting ends of the coupling brackets 11, and rigidly secured thereto by the outer of the set screws thereof. The brick work of the improved arch is 20 made up preferably of hanger blocks 15 and 16, underfacing blocks 17, corner facing blocks 18, crowning blocks 19 and usually more or less filling-in bricks 20, all of which are preferably made of clay, baked and 25 treated in the manner of fire bricks, so that they will stand very great heat.

The hanger blocks 15 have reversely projecting flanges both at top and bottom, or in other words, at both the top and bottom they 30 are of T-shaped formation. The upper flanges of the said blocks 15 are arranged to fit between channels formed by the adjacent supplemental beams 10 and to rest upon and interlock with the lower flanges thereof. 35 The outer edge blocks 16 are channeled in one face only, that is, each is substantially one-half of one of the blocks 15 that is made a little wider and is partly embedded in the walls of the masonry, as best shown in Fig. 40 2. The intervening blocks 17, on their upper sides, are formed with T-shaped flanges that slide into the channels formed by the depending T-shaped portions of the hanger blocks 15 and 16 and interlock therewith and 45 rest upon the lower flanges of the said hanger blocks with freedom, of course, for sliding movements into position and from position. The said blocks above noted are, of course, positioned in close contact. The 50 innermost hanger blocks 17 are supported by the detachable beam tips 10^a. The corner facing blocks 18, instead of having T-shaped upper end flanges, are formed with T-shaped seats that terminate short of the 55 front ends thereof, but adapt them to be slid onto the lower flanges of the innermost hanger blocks 17, which latter, as just above noted, are supported by the said beam tips. Hence, the said corner blocks are indirectly 60 supported from the said beam tips 10^a, and the said beam tips are protected from intense heat by said corner blocks as well as by the innermost hanger blocks. In fact, it will be noted that no parts of the metallic support- 65 ing beam are exposed to the direct action of

the flames of the furnace. The crowning blocks 19, in vertical section, are L-shaped so that they fit over and rest upon the projecting ends of the innermost hanger blocks 15 and 16. The space between the tops of 70 the blocks 19 and the flues, is filled in by ordinary fire brick 20. Slight space is left between the corner facing blocks and the crowning blocks, so that the former will be free from the weight of the latter. 75

The corner facing bricks 18 will be subjected to the most intense heat and will be burned away faster than any of the other blocks, and hence, will require more frequent replacement. Obviously, these corner blocks 80 may be very quickly and easily replaced and without removing any of the other blocks. Moreover, if these blocks should be so badly burned away that the flames would melt the ends of the beam tips 10^a, these latter may 85 be also easily cheaply and quickly replaced by others of like character. Obviously the construction is also such that any or all, for that matter, of the exposed arch blocks may be replaced. When they are hung, as described, they afford a very efficient arch and 90 thoroughly protect the metallic supporting beams. 95

Fig. 4 shows hanger blocks and underfacing blocks of the same general construction 100 as above described, but slightly modified so that sharp angles are avoided in the weaker portions of the blocks. In the said modified construction, Fig. 4, the hanger blocks 15^a have rounded upper surfaces and the upper and lower flanges are united to the vertical portions thereof by rounded surfaces that avoid sharp angles. Likewise, the underfacing blocks 17^a have their vertical webs 105 united to the upper flanges and body portions by rounded surfaces which avoid the sharp angles. Sharp angles, as is well known, render the flanges more liable to be broken off than where the joining surfaces are rounded. 110

As is evident, preferably by reference to Figs. 1 and 3, the corner blocks 18 and underfacing blocks 17 may be slid to and from position under the crowning blocks 19. 115

When the arch is complete, the metal beams of the arch, as already fully described, are not in contact with any arch block that is exposed to the direct action of the flames, and hence, are well protected from the heat. With this double layer arrangement of the blocks in the arch, not only is the life of the arch very greatly increased but replacement of blocks is made an easy matter. The manner in which the undersurfacing blocks or corner blocks may be easily 120 applied and removed has been stated. Attention is called to the fact that with the arrangement of blocks described, even if the bodies of the underfacing blocks should be burned away leaving only the necks thereof 125 130

interlocked with the hanger blocks, there would still be left a fire arch as good as any of the standard arches made up of a single layer of blocks. This improved arch will 5 therefore last for a comparatively long time and may be used for a considerable time even after the underfacing blocks have been burned away. This will give plenty 10 of notice in advance that the arch must be soon repaired, and moreover, will usually 15 make the possible life of the arch long enough so that repairs therein will not be necessary except at times when it is necessary to shut down the boiler for repairs in the boiler itself.

With the customary single layer arch, it has been necessary to frequently shut down the boiler and put out the fire at times when no boiler repairs were necessary and where 20 the shut down with the result of loss of time, waste of coal and expense generally, was due solely to repairs required in the fire arch itself.

What I claim is:

25 1. A fire arch for furnaces comprising hanger blocks supported in an upper layer, and underfacing blocks interlocked to and detachably hung from said hanger blocks and forming a lower layer to be exposed to the flames.

30 2. A fire arch for furnaces comprising hanger blocks supported in an upper layer, and underfacing blocks interlocked to and detachably hung from said hanger blocks and forming a lower layer to be exposed to the flames, the said hanger and underfacing blocks having joints that are lapped in a vertical direction with air spaces between said blocks in the vicinity of their 40 interlocking joints.

35 3. A furnace arch comprising laterally spaced beams, hanger blocks slidably hung on said beams and forming an upper layer, and underfacing blocks interlocked with and detachably hung from said hanger blocks and forming a lower layer to be exposed to the flames.

40 4. A furnace arch comprising laterally spaced beams, hanger blocks slidably hung on said beams and forming an upper layer, underfacing blocks interlocked with and detachably hung from said hanger blocks and forming a lower layer that is exposed to the flames, the inner members of said hanger blocks being projected rearward of the inner ends of said beams, and corner facing blocks detachably hung on the projecting ends of said hanger blocks.

45 5. A furnace arch comprising laterally spaced beams, hanger blocks slidably hung on said beams and forming an upper layer, underfacing blocks interlocked with and detachably hung from said hanger blocks and forming a lower layer that is exposed to the flames, the inner members of said hanger

blocks being projected rearward of the inner ends of said beams, corner facing blocks detachably hung on the projecting ends of said hanger blocks, and an apron wall supported by the inner ends of said beams, the 70 said underfacing blocks and corner blocks being slideable from position on said hanger blocks without disturbing the apron wall.

6. A fire arch for furnaces comprising an upper and a lower layer of fire blocks, the 75 upper layer having suitable supporting means, the said two layers of blocks having interlocked and interlocked T-shaped neck portions which connect the said upper and lower blocks with vertically staggered 80 joints and permit sliding movements of said lower blocks in respect to said upper blocks.

7. A furnace arch comprising transverse main hanger beams, laterally spaced supplemental beams underlying said main beams, said supplemental beams having replaceable 85 end tips detachably secured to the inner ends thereof, hanger blocks slidably interlocked to said supplemental beams and the 90 beam tips thereof, underfacing blocks slidably locked to said hanger blocks and corner facing blocks detachably supported by the innermost of said hanger blocks.

8. A furnace arch comprising transverse 95 main hanger beams, laterally spaced supplemental beams underlying said main beams, said supplemental beams having replaceable end tips detachably secured to the inner ends thereof, hanger blocks slidably interlocked 100 to said supplemental beams and the beam tips thereof, underfacing blocks slidably locked to said hanger blocks and corner facing blocks detachably interlocked to the innermost of said hanger blocks, and approximately 105 L-shaped crowning blocks set over said corner facing blocks and resting on the innermost of said hanger blocks.

9. The combination with suitably supported laterally spaced hanger beams having replaceable end tips detachably secured to their inner ends, hanger blocks slidably hung on said beams and their replaceable end tips, and underfacing blocks slidably and replaceably hung on said hanger blocks. 110

10. The combination with suitably supported laterally spaced hanger beams having replaceable end tips detachably secured to their inner ends, hanger blocks slidably hung on said beams and their replaceable end tips, underfacing blocks slidably and replaceably hung on said hanger blocks, and corner blocks hung on the end members of said underfacing blocks.

11. The combination with suitably supported laterally spaced flanged beams, of hanger blocks slidably hung on the flanges of adjacent beams constituting an upper layer, and having independent flanged neck portions of reduced width, and underfacing 125 130

blocks constituting a lower layer and having at their upper portions flanged necks of reduced width arranged to detachably interlock with and slide between the flanged necks of adjacent rows of hanger blocks.

12. A fire arch comprising laterally spaced beams, hanger blocks detachably hung from said beams and constituting an upper layer and underfacing blocks detachably hung from said hanger blocks and constituting a lower layer.

13. A furnace comprising parallel supporting beams, hanger blocks hung from said beams, under facing blocks interlocked

with and hung from said hanger blocks, corner facing blocks interlocked to the end members of said hanger blocks, and crowning blocks applied on the inner members of said hanger blocks, the said corner blocks projecting inward of said crowning blocks and serving as flame deflectors to protect said crowning blocks. 15

In testimony whereof I affix my signature in presence of two witnesses.

MICHAEL LIPTAK.
